UNITED STATES PATENT OFFICE.

HARRY A. KAST, OF ELMHURST, NEW YORK, ASSIGNOR TO THE KALBFLEISCH CORPORATION, OF NEW YORK, N. Y., A CORPORATION OF NEW YORK.

CARBOY.

Application filed July 11, 1924. Serial No. 725,501.

To all whom it may concern:

Be it known that I, HARRY A. KAST, a citizen of the United States, and a resident of Elmhurst, Queens County, New York, ⁵ have invented an Improvement in Carboys, of which the following is a specification.

My invention relates to improvements in carboys. Commercial carboys comprise a bottle which is encased in a box, and it is ¹⁰ necessary to have the enclosing box of such a structure that it will be passed by the Interstate Commerce Commission, that it will protect the interior bottle as far as possible against breakage, and it must not be ¹⁵ so expensive as to prevent its wide use. In practice it has been found difficult to meet these requirements and produce a box of sufficient strength and cheapness which would cushion the bottle so as to protect it ²⁰ against shock in all directions. Furthermore, such carboys are used largely for acids, and even if the bottle is not broken there is likely to be such spilling of acid as will attack any metallic parts of the box, ²⁵ and so it is necessary to have the casing substantially acid-proof. In previous attempts to cushion the bottles, cushions have been used beneath and at the sides of the enclosing box or casing, but they have been so ³⁰ disposed that under severe shocks in certain directions, the cushion would permit the bottle to come into such solid contact with the bottom or side of the casing, or with the floor or ground as to cause break- ³⁵ age.

My invention is intended to obviate the difficulties above named, and produce a simple, not too expensive carboy in which the material is all acid-proof and in which ⁴⁰ the bottom, sides, and a part of the top of the bottle are cushioned effectively so that the bottle will resist great shock in any direction without breaking. In carrying out this result, I have wooden cushions prefer- ⁴⁵ ably in the form of laminated hard wood springs, the bottom cushions crossing one another at right angles below the bottle and being supported at their outer ends only, thus giving them the necessary reinforce- ⁵⁰ ment by crossing them, and the requisite elasticity by supporting them at their extreme ends without any center support. I also use the side cushions of like character which are arranged vertically and prefer-

ably disposed at angles to the bottom ⁵⁵ cushions, these side cushions being secured at the bottom to abutments which lie in a lower plane than the supports of the crossing bottom cushions, and being secured at the tops by abutments which extend within ⁶⁰ the vertical side planes of the bottle. Thus the side cushions converge inwardly above and below the bottle so as to cushion it not only against side thrust, but to hold it resiliently against end thrust, and as the bottoms of the side cushions are secured at a lower plane than the supports of the crossing bottom cushions, it will be seen that if the carboy as a whole is dropped, the shock ⁶⁵ will be distributed between the side and bottom cushions, and thus sufficient strength and great resiliency are afforded so that breakage is unlikely. All of which will be better understood from the description ⁷⁰ which follows.

Reference is to be had to the accompanying drawings forming a part of this specification, in which similar reference characters indicate corresponding parts in all ⁷⁵ the views.

Figure 1 is a plan view of the carboy embodying my invention with the cover removed.

Figure 2 is a vertical cross section on the line 2-2 of Figure 1, with the cover in ⁸⁰ place.

Figure 3 is a horizontal cross section through the carboy, and

Figure 4 is a broken section on the line ⁸⁵ 4-4 of Figure 3.

The bottle 10 of the carboy can be any conventional bottle, and it is held in an outer casing 11, usually styled a box, and this can be of any usual or preferred construction. Arranged horizontally near the box bottom ⁹⁰ 95 are transverse cushions 12 which are of laminated structure, preferably thin oaken strips, and the two cushions or springs cross one another at right angles, are held well above the bottom or floor of the box 10, and are supported at their ends only on blocks 13.

Arranged vertically in the box and disposed between the cushions 12, are similar cushions 14, preferably of laminated wood, which at their lower ends are secured to the inner sides of the abutment blocks 15, and at their upper ends are secured to the corner pieces ¹⁰⁰ ¹⁰⁵

16 which are similar to the pieces 15. These blocks 15 and 16 are disposed in sets one above the other as shown, and they project into the box so that their inner edges are 5 within the vertical plane represented by the sides of the bottle 10. Thus the bottle by its pressure bulges out the sides of the cushions 14 so that these act on the bottom and top of the bottle to prevent its sliding 10 lengthwise.

It will be noticed by reference to Figures 2 and 4 that the blocks 12 are substantially higher than the blocks 15, so that the springs or cushions 12 lie in a plane noticeably higher 15 than the tops of the said blocks 15. Consequently in case of severe shock which might cause the cushions 12 to buckle sufficiently to permit the bottle 10 to strike the floor of the box and break the bottle, this 20 is prevented by the auxiliary cushion effect of the springs 14 which absorb part of the shock.

It will be seen that if the cushions 12 and the blocks 15 are on substantially the same 25 plane, in such a case there will be a substantially dead point between the lower corners of the bottle and the blocks 15 which by reason of the lack of resilience would permit the breaking of the bottle under such circumstances.

When the carboy is to be used, the box 30 15 and cushions 14 are placed in position, the bottle inserted, and the blocks 16 then forced into the top of the box and fastened, causing 35 the bulging of the cushions as described. The blocks 16 are then fastened in place and a cover 17 placed over the top as usual, this having sufficient clearance 18 to prevent any 40 contact between the neck of the bottle and the cover.

From the foregoing description it will be seen that I have devised a simple and not expensive carboy in which the bottle is nicely

cushioned against thrusts in any direction, that it can be made of wood entirely, 45 and makes a strong, simple structure.

I claim:—

1. A carboy comprising a bottle and an enclosing box or casing therefor, abutments on the casing bottom opposite the plane 50 sides thereof, transverse cushions supported on the abutments and extending beneath the bottle leaving a clear space beneath near the middle portions, vertical acid resisting cushions each comprising a flat strip of material, 55 said cushions being unconnected with each other leaving a clear space between them, the lower ends of said cushions being secured at points within the plane of the bottle sides and at a lower point than the support for 60 the bottom cushions, and acid resisting corner blocks in the upper corners of the casing of a size to bring the upper ends of the vertical cushions within the plane of the bottle sides. 65

2. A carboy comprising a bottle and an enclosing box or casing therefor, abutments on the casing bottom opposite the plane sides thereof, transverse cushions supported on the abutments and extending beneath the 70 bottle leaving a clear space beneath their middle portions, vertical cushions of acid resisting material arranged opposite the casing corners, the lower ends of the vertical cushions being secured at points within the 75 plane of the bottle sides and at a lower point than the supports for the bottom cushions, and acid resisting corner blocks in the upper corners of the casing of a size to bring the abutting upper ends of the vertical cushions within the plane of the bottle sides. 80

In testimony whereof, I have signed my name to this specification this 8th day of July, 1924.

HARRY A. KAST.
